UNITED STATES PATENT OFFICE.

LYLE H. FISHER, OF KANSAS CITY, MISSOURI, ASSIGNOR TO AMERICAN OPTICAL COMPANY, OF SOUTHBRIDGE, MASSACHUSETTS, A VOLUNTARY ASSOCIATION OF MASSACHUSETTS.

EDGING MACHINE.

Application filed October 30, 1922. Serial No. 597,879.

This invention relates to improvements in edging machines, and has particular reference to a novel and improved form of machine especially adapted for use in the edging of ophthalmic lenses.

One of the principal objects of the present invention is the provision of a simple and efficient machine which may be readily manually operated and which will serve to form a satisfactory edge of desired configuration on an ophthalmic lens.

A further object of the invention is the provision of a machine of the type above set forth which may be employed for either bevel or rimless edging, as may be desired.

Other objects and advantages of the present improvement should be readily apparent by reference to the following specification taken in connection with the accompanying drawings, and it will be understood that I may make any modifications in the specific details of construction shown and described within the scope of the appended claim without departing from or exceeding the spirit of the invention.

Figure I represents a front view of one embodiment of my improvement.

Figure II represents a plan view thereof.

Figure III represents a vertical sectional view taken as on the line III—III of Figure II.

Figure IV represents a fragmentary sectional view through the contact shoe and arm and associated parts.

Figure V represents a plan view showing the machine in operation and with the adjustable contact shoe arm of Figure IV.

Figure VI represents a plan view of the machine of Figure V employed for bevel edging purposes.

Figure VII represents a fragmentary sectional view of a slightly different continuous cross feed for the carriage.

In the drawings, the numeral 1 designates the base of my improved device which is capable of attachment to a bench grind-stone base, or the like, the device being intended to be secured in fixed position as respects the rotating stone 2 of suitable abrasive for grinding off the edge or corner of the ophthalmic lens, watch crystal or other similar glass member 3.

The base 1 is intended to be put in such relation to the stone 2 that the guide arc of travel of the supplemental base plate 4

carrying the machine proper will have its center just at the surface of the grind-stone at the approximate point where it would be engaged by the lens 3, as is indicated by the dotted lines in Figure V of the drawing. The purpose of this is to allow of suitable oscillatory or angular adjustment of the member 4 on the base 1, dependent on whether the machine is being used for rimless or for bevel edging without shifting the lens across the face of the stone on account of such angling adjustment. Suitable guide means such as the slot 5 may be employed to control the relative movement of the main and supplemental bases, clamp screws or similar devices 6 serving to secure the parts in desired angularly adjusted position while the latch member 7 carried by the base 1 and selectively engaging the notches 8 in the edge of the plate 4 serves to secure the parts in right angle relation to the stone for rimless edging or at the normal angle for regular bevel edging.

Rising from the member 4 are the bracket ears 9 for the spindle 10, which in Figure III is shown as threaded to engage the feed nut 11 driven as by a sprocket 12. The spindle 10 is rotatively held in the ear 9 as by the screw 13 engaged in the groove 14 and has on its opposite outer end the operating hand wheel portion 15 locked in adjustment as by the releasable latch 16 engaged in the notch 17 of the handle. This is to enable the handle to be released and manually rotated if it is desired to adjust the lens to any definite relation to the grind-stone in the feed toward the right and to enable the handle to be turned to draw back the lens carriage and associated parts to the left when they have reached their limit of movement toward the right. The lens carriage 18 itself is of U-shaped formation having the nut 11 fitting into the furcation or notch 19 at the bottom having its arms connected by the cross braces 20 and bearing at its upper end the lens holding mechanism. This mechanism comprises at the one end the spindle or rod member 21 urged inwardly as by the spring 22 bearing against the shoulder 23 and bearing on its inner end the rotatable lens clamp pad 24 and on its outer end the actuating cam 25 cooperating with the cam surface 26 on the member 18, so that giving a half turn to the cam member 25 will draw the lens 110

clamp section 24 into releasing position, while continued rotation or reverse turning will allow the cam 25 to ride down on the cam surface 26 as urged by the spring 22 until the pad 24 is brought into correct clamping engagement with the work piece or lens 3. Opposed to the pad 24 is a second lens clamp pad 99 carried by the drive spindle 27 preferably provided with a sprocket 28 connected by the chain 29 with the sprocket portion 12 of the feed nut 11 to drive the latter.

Power is applied to the spindle 27 as by a crank handle 30 removably secured on the outer end of the shaft 27, as by the set screw 31. This handle has the hub portion 32 which bears the set screw 31 and is formed with the pins 33 to engage sockets in the former 34. In operation the former and handle are placed together with the pins interlocking with the former and the parts then slipped onto the spindle or shaft 27 and the set screw or locking device 31 tightened to secure the combined handle and former in place. The member 27 is preferably formed with a socket 35 into which the locking member 31 fits so that the former will be in definite relation to the lens clamp pads so that a lens may be properly centered between the lens clamp pads and the former will then be in definite relation to the lens.

It is to be noted that the frame 18 is supplied with a keeper 36 adapted to be engaged by the latch 37 to hold the frame in retracted position or swung back out of engagement with the stone, as indicated in Figure II, a spring 38 tending to actuate or swing the carriage 18 toward the stone when the latch is released with relatively light pressure.

To control the size and shape of the lens being operated upon, I preferably pivot on the supplemental base 4 the bracket 39 adapted to be locked in desired angularly adjusted relation as by the latch member 40 fitting down through a slot in the back of the base of the member 39 and into selected apertures or notches 41 in the base 4. This member bears at its upper end the swivelled interiorly threaded bushing 42 provided with the graduated head 43 which serves both to rotate the bushing and to cooperate with the pointer 44 to denote the amount of rotation. Threaded into the bushing is the shank or stud 45 on the contact shoe 46 which projects in its normal or average adjustment substantially into line with the pivot 47 of the bracket 39 and is provided with the pin or pins 48 sliding in the bracket 39 to prevent rotation or twisting of the contact shoe 46 as the head 43 and bushing 42 are turned so that rotation of these parts gives a definite in and out adjustment to the position of the contact shoe. It is to be

understood that the former 34 rides on its shoe 46 and the shape and size of the finished lens is thus controlled thereby.

In the operation for what is known as rimless edging the lens having been placed in position between the clamp pads, the table 4 is set square with the edge of the stone 2 and the bracket 39 is set with the contact face 49 parallel with the edge of the stone. The crank handle 30 is then turned rotating the lens against the stone and the pattern or former 34 against the face 49 of the contact shoe until the lens is properly edged to correct size. During this operation the chain connection between the sprocket on the spindle 27 and the sprocket on the feed nut 11 will have caused the lens to move slowly across the face of the stone and prevent grooving of the stone.

In the event that it is desired to bevel edge the lens, the lens is preferably first edged to the rimless form, after which the table 4 is swung around to the proper angle to the stone, preferably as gaged by the latch 7 and notch 8 on the table. If desired the former 34 may then be removed and the lens allowed to float against the stone impelled by the light force of the spring 38,

when an equal amount will be ground off all around the periphery of the lens. If preferred to make use of a former in connection with the placing on of the bevel, or if it is the intention to bevel off the lens after cutting and without first rimless or flat edging it, a former may be made use of of substantially the same curve as the base curve of the lens itself, as is indicated in connection with Figure VI, this former preferably having a bevel edge as at 50 riding on the shoe 49, the bracket 39 in this instance being adjusted after angling of the table 4 so that its face will again be parallel with the face of the stone. With the parts in this position the carriage may be fed back and forth along the guide rod 10 and the lens be guided over the face of the stone to be bevelled to the exact and correct size and angle. After one side of the lens has been bevelled the member 4 is then turned and the bracket 39 re-angled to again bring the face of the contact shoe parallel with the stone, when the procedure is as before, placing a bevel on the second or other edge of the lens.

In Figure VII it is to be noted that I have shown a slightly modified form of feed, in which instead of making use of the screw feed and nut, I make use of the barrel 51 having the double spiral track 52 formed thereon, in which rides the guide block 53 rotatably secured on the lower end of the pin 54 on the lever 55 which is carried by the frame. This lever may be raised to bring the block out of engagement with the groove 52. When the block is brought

downward in engagement and the member 51 rotated the barrel cam and associate parts will be laterally shifted or reciprocated back and forth automatically on the guide 10 as 5 the crank 30 is rotated, the barrel cam 51 being provided with the sprocket 56 over which the chain 29 may pass to operate the latter.

From the foregoing description taken in 10 connection with the drawings, the construction and operation of my improved hand operated combined automatic rimless and bevel edging machine should be readily understood, and it will be seen that I have 15 provided an extremely simply constructed but efficient device of this character having a cross feed which will prevent grooving of the stone, having guide members to insure

correct size and shape of the lens during the edging operation and in which any regular or irregular form of lens may be readily and satisfactorily edged.

I claim:

In a device of the character described, an attachment base plate adapted to be attached 25 to the frame of a grindstone, a second plate pivoted to the first plate and adapted to be moved in an arc about its pivot on the first plate, a swinging lens clamp on the second plate, a former on the lens clamp, a contact 30 for the former mounted upon the second plate, and means for moving the face of the contact so that it will be parallel with the face of the grindstone in any position to which the pivoted plate is moved.

LYLE H. FISHER.
